United States Patent Office

Des. 192,634
Patented Apr. 24, 1962

192,634

AUTOMOBILE

Walter H. Korff, Burbank, Calif.

Filed Apr. 19, 1960, Ser. No. 60,249

Term of patent 14 years

(Cl. D14—3)

Fig. 1

Fig. 2

The dominant features of my design reside in those portions shown in full lines.

I claim:

The ornamental design for an automobile, as shown and described.
